Primary Examiner — Jennifer L Watkins

Assistant Examiner — Samantha Lynne Brodowski

(57) **CLAIM**

The ornamental design for a crossbody bag, as shown and described.

DESCRIPTION

1. Crossbody bag
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Enlarged
- 1.10 : Enlarged

The parts shown by means of broken lines in the reproductions are not part of the claimed design; fig. 1.9 and fig. 1.10 are the enlarged views of the portion taken at line 9 in fig. 1.1 and line 10 in fig. 1.2; the dash-dot-dash lines in reproductions 1.1, 1.2, 1.9, 1.10 and the number “9” in fig. 1.1, number “10” in fig. 1.2 are included to show a partially enlarged view only and form no part of the claimed design.

1 Claim, 10 Drawing Sheets
